UNITED STATES PATENT OFFICE

ANDREW CHRISTIAN ANDERSEN, OF DETROIT, MICHIGAN, ASSIGNOR TO TERNSTEDT MANUFACTURING COMPANY, OF DETROIT, MICHIGAN, A CORPORATION OF MICHIGAN

WINDOW REGULATOR MECHANISM

Application filed May 14, 1928. Serial No. 277,491.

This invention relates to a window regulator mechanism which is adapted for use in regulating and controlling the windows of an automobile.

5 The invention aims to provide a window regulator mechanism which involves an operable connection which is irreversible; more specifically, the mechanism involved is such as to effect a positive lock against movement of the window after it has been adjusted to any given position, but which at the same time permits the window to be readily adjusted by the operation of a suitable regulator handle or the like.

15 In the accompanying drawings:

Fig. 1 is a side elevation of the mechanism illustrating the same connected to a window and showing in dotted lines several positions of adjustment.

20 Fig. 2 is a view showing the operable connection of the mechanism, this view being taken from the opposite side of Fig. 1.

Fig. 3 is a sectional view taken substantially on line 3—3 of Fig. 1.

25 Figs. 4 and 5 are detail views of one of the operable parts.

Figs. 6 and 7 are views illustrating a modified form of the invention, these two figures showing the operable connection in different positions.

30 Fig. 8 is a detail view of the driving connection of the form of Figs. 1 and 2, illustrating the connection in a position different than that shown in Fig. 2.

35 The mechanism may be mounted in a door or the side of an automobile body on a suitable board 1, customarily termed the lock-board. The mechanism includes a suitable supporting plate 2 which may be secured to

40 the lockboard as by means of screws 3 taken through suitable apertures. A toothed segment or rack 4 having teeth 5 is pivotally mounted to the plate 2 as by means of stud 6. Secured to the segment is an arm 7 having a suitably shaped stud or roller 8 which

45 engages in a track or channel 9 secured to the bottom of the window 10.

50 It is to be appreciated that as the segment is moved rotatably upon its mounting, the arm 7 effects a raising and lowering of the

window, several positions of which are shown in dotted lines in Fig. 1. The stud 6 may be fixed to rotate with the segment, and a coil spring 11 may be employed to counterbalance the weight of the window. 55 One end of this coil spring may be fitted into a slot in the stud and the other end may be hooked over a fixed pin 12 on the plate 2. When the window is lowered the spring is flexed so that it acts to aid in lifting the window when the window is again raised. 60

For the purpose of actuating the segment an operating part 15 is provided having a pair of oppositely disposed eccentrically arranged pins 16 and 17. This operating part 65 may be journaled in a cup shaped member 18 which may be flanged as at 19 and secured to the plate 2 by suitable screws or the like 20. The plate 2 may be a stamping and may be pressed out to provide a recessed formation 21 for receiving the flange or the cup. A suitable operating handle 23 is fixed to the exposed end of the member 15.

As shown in Figs. 2 and 3 the pins 16 and 17 are positioned so as to engage with the teeth 5 on the segment. For the purpose of providing a suitable cover or protector for the point of engagement the plate 2 may be stamped out as at 22. In the operation of the mechanism, rotation of the handle 23 will cause the pins to alternately engage the segment teeth and move the segment. The teeth are cut into the segment a sufficient distance to permit the pins to move down between two teeth, without binding against the bottom of the furrow formed by the two teeth. This is illustrated in Fig. 8. Upon continued rotation of the handle the pins 16 and 17 alternately engage teeth on the segment and give it a rotative movement 80 around its mounting.

When the window is in any given adjustment, the two pins serve to positively lock the window from movement by forces applied to the window, other than through the handle 23. The locking position of the pins is shown in Fig. 2. Here the two pins are lined up substantially on the pitch line of the teeth, or in other words, on a dead center line. Any force which tends to rotate 100

the segment is overcome by the pins, and this force creates no turning moment on the part 15.

In actual operation it may happen that when the window is adjusted the pins take the position shown in Fig. 8. Under this condition the window may jar down a trifle until the pins become aligned, whereupon no further movement is permitted. This trifle movement of the window is not sufficient to interfere with the practicability of the mechanism. When the window is raised into an entirely closed position its upper edge is confined in a channel of some depth, and the trifle of movement permitted by the pins will not permit the window to move out of the channel.

In order to limit the extreme movements of the segment, and prevent it from disconnection with the pins, the segment may be provided near each end with a recess 25 of less depth than the teeth. When one of the pins 16 or 17 moves into this recess further rotation of the operating handle is prevented because the recess is not deep enough to permit the eccentric pin to complete its circle of movement.

The modified form of the invention, as shown in Figs. 6 and 7, embodies a segment 4a provided with internally extending teeth 5a as distinguished from the form just described having external teeth. In this form there is a rotating operating element 15a provided with eccentric pins 16a and 17a which are associated with the teeth in a manner similar to the manner in which the teeth and segment are associated in the above described form. In Fig. 6 the teeth are shown in locking position, whereas in Fig. 7 the pins are shown in one position which they assume during operation.

I claim:

1. A window regulator mechanism comprising, an adjustable member provided with rack teeth, means connecting the adjustable member with a window, a rotatable driving element having a pair of eccentrically disposed pins for engaging the teeth in the rack so that the rack is moved and the window adjusted upon actuation of the driving member, the depth of the teeth being sufficient to permit the eccentric pins to move in between any two given teeth, said rack being provided with a recess beyond the end tooth, which recess is of a depth less than the depth of the teeth so that when the rack approaches the end of its movement an eccentric pin may engage in such recess whereby further actuation of the parts is prevented.

60 2. A regulator mechanism for automobile windows or the like comprising in combination, a pivotally mounted segment having gear teeth thereon, a segment arm connecting the segment with a window, a driving element having a handle thereon journaled

adjacent the gear toothed portion of the segment, a pair of diametrically oppositely positioned pins or studs projecting from the driving element, said pins or studs being eccentric of the driving element, said pins projecting into the plane of the segment whereby the pins may engage between adjacent teeth thereon, said driving element being rotatable by its handle to cause rotating movement of the segment by the alternate engagement of the pins between the gear teeth on the segment to regulate the window, said driving element being on an axis located with respect to the gear teeth so that the two pins may simultaneously engage between the teeth on the segment with a line drawn through the center of the pins being substantially on the pitch line whereby force applied to the segment which tends to rotate the same is overcome by the pins with substantially no turning moment on the driving member to hold the window in any given position of adjustment.

In testimony whereof I affix my signature,

ANDREW CHRISTIAN ANDERSEN.
